UNITED STATES PATENT OFFICE

HENRY C. AVERY, OF NEW BRUNSWICK, NEW JERSEY, ASSIGNOR TO THE FLINTKOTE COMPANY, OF BOSTON, MASSACHUSETTS, A CORPORATION OF MASSACHUSETTS

FLOORING AND THE LIKE AND METHOD OF MAKING

Application filed May 10, 1924. Serial No. 712,264.

This invention relates to flooring and the like comprising a fibrous and asphaltic base and seeks to provide such a material presenting a highly ornamental effect. For this purpose the base material is provided with a grit facing of any desired color or colors which is then submerged with asphaltic material applied thereto. The surface thus presented is buffed to disclose portions of the grit to produce a multi-colored effect between the contrasting colors of the grit and the asphaltic material. The asphaltic material may then have channels cut in the surface thereof dividing it into tile-like portions of suitable design held in spaced relation by the uncut base material. These channels may then be filled with plastic of any desired color to define parting lines between the tile units.

For a more complete understanding of this invention reference may be had to the accompanying drawings in which

Figure 1 shows in plan a tile unit of the finished floor.

Figure 2 is a cross section through the asphaltic grit coated base for that unit on line 2-2 of Figure 1.

Figure 3 is a view similar to Figure 2 showing the grit surfacing coated so as to completely submerge the grit granules.

Figure 4 is a similar view showing the surface being buffed to expose the grit, thus giving the surface the appearance of Figure 1.

Figure 5 illustrates the manner in which the channels between the tile sections may be cut.

Figure 6 is a plan of the material showing the surface cut by the channels into tile simulating portions.

Figure 7 shows a portion of the completed flooring.

A sheet base comprising felted fibrous material, such as rag felt, as at 1, is coated with a heavy asphalt, such as blown asphalt, into the surface of which are partially embedded granules of any suitable type of grit as at 2. This may be crushed slate of one or more colors, stone, or any other suitable material which will give the desired color effects and which has the necessary texture to withstand

wear. The material thus prepared is coated over with material capable of bonding with the base such as asphaltic material, as for example, that known to the trade as K-B cement, which comprises an emulsion of normally adhesive asphalt with a colloidal material such as clay, with or without an inert filler. This material is applied to the exposed grit surface until the grit is entirely submerged, presenting the appearance shown in Figure 3 at 3. The exposed surface is then buffed off as by means of a buffing wheel 4 to remove some of the bituminous mixture, such as the asphalt emulsion, and also portions of the grit granules until a plane surface is presented showing both sections of the grit granules and the emulsion in the interstices therebetween, as shown in Figure 1.

A sheet material thus prepared may then be run under a suitable gang grinding machine having a series of spaced grinding wheels 5 thereon, as shown in Figure 5, and by means of these grinding wheels channels 6 may be cut through the surface of the material down approximately to the fibrous sheet material base.

The sheet may then be run in at an angle to the first line of grooves, thus defining geometrical patterns simulating tiles as shown at 10 in Figure 6, these being spaced apart by the channels 6. As shown the channels 6 are at right angles to each other defining square tile simulating portions, but it should be evident that they may be given any desired relation so as to produce any geometrical tile pattern. As shown in Figure 6 the base section is of sufficient size to form sixteen smaller tile units, but of course the base section might be larger or smaller as might be desired. Either before or after laying on the floor the channels 6 are filled with suitable plastic material which may be colored as desired so as to contrast with the tile simulating surfaces. The sections may be laid spaced apart either the same or a different distance from the width of the channels 6 and these spaces may also be filled with plastic which may be the same as or different from the plastic used for filling the channels.

As shown in Figure 7 the spacing of the

sections is greater than the spacing of the individual units of each section, these wider spaces 12 being filled with plastic which is of somewhat different appearance, as for example, of different color than in the channels 6. This, therefore, gives the effect of a series of large tiles each made up of a plurality of smaller tile sections and each of the smaller tile sections presenting a mottled appearance. It will thus be seen that a great variety of mottled tile effects may be produced by forming the flooring material according to the method hereinbefore described.

Having thus described certain embodiments of this invention it should be evident to those skilled in the art that various changes and modifications may be made therein without departing from its spirit or scope as defined by the appended claims.

I claim:

1. The method of making sheet flooring which comprises applying a granular facing to a sheet material base, submerging the granules in a layer of material capable of bonding with said base, and buffing the surface to expose sections of the granules.
2. The method of making flooring which comprises applying a granular facing to a sheet material base, submerging the granules in a layer of material capable of bonding with said base, buffing the surface to expose sections of the granules, and cutting channels through the surface portion of the material and filling the channels with plastic material.
3. The method of making flooring which comprises applying a granular facing to a sheet material base, submerging the granules in a layer of material capable of bonding with said base, buffing the surface to expose sections of the granules, cutting channels through the surface to define geometrical areas, and filling said channels with plastic material.
4. The method of making flooring which comprises applying a granular facing to a sheet material base, submerging the granules in a layer of material capable of bonding with said base, buffing the surface to expose sections of the granules, cutting channels through the surface to define geometrical areas, and filling said channels with plastic material presenting a surface coloring different from that of said areas.

5. The method of making flooring which comprises saturating and coating fibrous sheet material with asphaltic material, applying a layer of granular material to the coating, and submerging the granular material with more asphaltic material, removing the exposed surface to disclose areas of sections of the granular material interposed with areas of asphaltic material, cutting spaced channels into the surface to define

geometrical areas, and filling said channels with material presenting a surface appearance different from that of said areas.

6. Sheet flooring comprising an asphaltic base having a substantially smooth surfacing layer thereon showing a mixture of asphaltic and granular material, said layer having channels therein defining tile-simulating areas.

7. Sheet flooring comprising an asphaltic base having spaced surfaced areas showing a mixture of asphaltic and granular material, the spaces between said areas being filled with other material.

8. Flooring comprising a fibrous sheet base saturated with waterproofing material and having projecting from its upper face bonded thereto spaced tile simulating portions formed of a plastic and granular material embedded therein, the exposed surfaces of said tile portions presenting interspersed areas of plastic material and sections of granular material, and plastic filling the spaces between said portions.

9. The method of making a floor unit consisting of placing a layer of plastic material with stone particles near the upper surface, permitting the same to harden, finishing the surface so as to expose sections of the particles, cutting kerfs or grooves in said layer and filling the grooves with plastic material.

10. The method of making sheet flooring which comprises applying a granular facing to a sheet material base, submerging the granules in a layer of material capable of bonding with said base, buffing the surface to expose sections of the granules, and cutting channels through the surface portion of the material to simulate tiles.

11. The method of making flexible sheet flooring which comprises applying plastic material and granular grit in a substantially smooth layer to a face of flexible sheet foundation material, and forming grooves in said layer to bring the areas between said grooves into relief in a manner to simulate tiles.

In testimony whereof I have affixed my signature.
